WIND OPERATED ROTATABLE SIGN

James J. Pearson, Tulsa, Okla.

Application November 8, 1944, Serial No. 562,484

3 Claims. (Cl. 40—39)

1

The device forming the subject matter of this application is a sign, and one object of the invention is to provide a novel alternating arrangement, vertically considered, of fixed and rotatable display members, the rotatable members being mounted to turn in opposite directions, responsive to the wind, about a vertical axis.

Another object of the invention is to improve the construction of the fixed and rotatable members and the means for mounting them.

Another object of the invention is to supply a device of the class described, which will provide a large amount of advertising space, capable of being viewed from any point of the compass.

Within the scope of what is claimed, the structure described and shown may be changed, without departing from the spirit of the invention.

In the accompanying drawings:

Fig. 1 shows in top plan, a device constructed in accordance with the invention;

Fig. 2 is a side elevation wherein parts are shown in section.

In carrying out the invention, there is supplied a vertical post P, comprising a tubular standard 1 having its foot mounted in a foundation 2. At its upper end, the standard 1 carries a fixed, annular head 3. The numeral 4 designates a fixed, vertical, hollow shaft, having its lower end received in the standard 1, the shaft being connected to the standard as indicated at 5.

The device includes a fixed lower member 6, which is horizontally disposed. The fixed lower member 6 comprises a loop-shaped body 7 of considerable height, and capable of affording advertising space. A brace block 8 is secured at 9 within the body 7, midway between the ends of the body. The shaft 4 passes through the brace block 8, and the securing elements 9 which hold the brace block in the body 7 also connect the fixed, elongated lower member 6 to the shaft 4, the lower member resting on the head 3 and on the upper end of the standard 1. At its ends, the body 7 of the fixed lower member 6 is equipped with outstanding hangers 10, whereon pendants 11, preferably of cylindrical form, are pivotally suspended.

The fixed lower member 6 supports a lower rotor 12 for turning movement about a vertical axis. The lower rotor 12 comprises a hub 14, rotatably mounted on the shaft 4, the inner ends of arms 15 being secured to the hub, the arms being radially disposed. There are upper arms and lower arms 15, the outer ends of the upper arms being connected by a ring 16, and the outer ends of the lower arms being connected by a ring

2

17. Vanes 18 are secured between the arms 15 and are so pitched, horizontally, that, receiving the wind, they will cause the lower rotor 12 to rotate about a vertical axis.

5 A fixed upper member 19 is provided, and is disposed at right angles to the fixed lower member 6. The fixed upper member 19 is constructed like the fixed lower member 6, parts already described being designated by numerals hereinbefore used, but primed in connection with the fixed upper member. The fixed upper member 19 is disposed directly above the rotatable lower member 12.

15 Above the fixed upper member 19 is located a rotatable upper member 20, constructed like the lower rotatable member 12. Numerals used in connection with the rotatable lower member 12 have been primed in connection with the rotatable upper member 20. The vanes 18' of the rotatable upper member 20 are so pitched that the upper member will rotate in a direction opposite to that in which the lower member rotates.

20 The upper rotatable member or rotor 20 is held on the shaft 4 for rotation, through the instrumentality of a cap 21 threaded on the shaft.

25 The rings 16' and 17' of the upper rotor 21 carry upstanding angle brackets 22, to which is secured an annulus 23, of such height as to afford plenty of space for advertising material.

30 Anti-friction bearings 24 may be employed, wherever necessary.

35 The annular head 3 of the standard 1 carries a nipple 25, through which extend conductors 26, electrically connected to lamps 27 on the sides of the fixed members 6 and 19. There may be as many or as few of the aforesaid lights 27 as desired, and they may be located as preferred. Any suitable means may be supplied whereby the rotors 12 and 20 may rotate and still have electrical 40 current fed to them through the conductors 26. That is an electrician's detail forming no part of the present application.

45 Advertising or display material may be placed on the fixed lower member 6, on the lower rotor 12, on the fixed upper member 19, on the upper rotor 20, and on the annulus 23. The pendants 11 also make advertising or display material.

50 Both sides of the fixed lower member 6, and the ends thereof are available for advertising or display material, and the same observation holds true with respect to the fixed upper member 19. The vanes 18 and 18', of the rotatable members 12 and 20, respectively, may carry advertising material or the like, which will be displayed as the 55 rotors turn, responsive to the action of the wind.

upon them. The effectiveness of the display is promoted, also, by reason of the fact that the lower member 6 and the upper member 19 are arranged at right angles to each other, in the form of a cross.

Generally stated, the device forming the subject matter of this application includes display elements so arranged with respect to each other, and capable of rotation in some instances, that it will be practically impossible to view the device without being able to note all of the display or advertising material on it. The lamps 27 furnish the necessary illumination at night, and the device will exercise its function after sun-down as well as during the daytime.

What is claimed is:

1. A sign comprising a post, fixed, horizontally elongated upper and lower display members em-

bodying radiating arms secured to the post, upper and lower display rotors journaled on the post, the lower rotor being disposed between the fixed members, and the upper rotor being disposed above the upper fixed member, and oppositely-pitched vanes incorporated in the rotors whereby the rotors will be wind-impelled to turn in opposite directions.

2. A sign constructed as set forth in claim 1, in combination with display pendants suspended from the outer ends of the fixed members and spaced horizontally from the outer ends of the fixed members.

3. A sign constructed as set forth in claim 1, in combination with a display annulus mounted on the upper portion of the upper rotor and standing therefrom.

JAMES J. PEARSON.
